FISHING LURE

Edward N. Campbell, 4068 NW. 61st 74126, and Bruce E. Long, 5523 Colfax Place 73112, both of Oklahoma City, Okla.

Filed Dec. 26, 1967, Ser. No. 9,916

Term of patent 14 years

(Cl. D22—28)

FIGURE 1 is a side elevation view of a fishing lure incorporating the design of the present invention.

FIGURE 2 is a top plan view of the fishing lure depicted in FIGURE 1.

FIGURE 3 is a bottom plan view of the fishing lure depicted in FIGURE 1.

FIGURE 4 is an end elevation view of the fishing lure depicted in FIGURE 1 as the lure appears when viewed from the trailing end thereof.

FIGURE 5 is an end elevation view of the fishing lure depicted in FIGURE 1 as the lure appears when viewed from the forward end thereof.

FIGURE 6 is a side elevation view of another embodiment of a fishing lure incorporating the design of the present invention.

FIGURE 7 is a top plan view of the fishing lure depicted in FIGURE 6.

FIGURE 8 is a bottom plan view of the fishing lure depicted in FIGURE 6.

FIGURE 9 is an end elevation view of the fishing lure depicted in FIGURE 6 as the lure appears when viewed from the trailing end thereof.

FIGURE 10 is an end elevation view of the fishing lure depicted in FIGURE 6 as the lure appears when viewed from the forward end thereof.

The dominant features reside in the solid line portions.

We claim:

The ornamental design for fishing lure, substantially as shown and described.
